UNITED STATES PATENT OFFICE.

JULIUS BRAUSE, OF HARTFORD, CONNECTICUT.

DESIGN FOR A WARDROBE.

45,445.

Specification for Design.

Patented Mar. 24, 1914.

Application filed January 20, 1914. Serial No. 813,340. Term of patent 7 years.

To all whom it may concern:

Be it known that I, JULIUS BRAUSE, a subject of the Emperor of Germany, residing at Hartford, in the county of Hartford and State of Connecticut, have invented a new, original, and ornamental Design for Wardrobes, of which the following is a specification, reference being had to the accompanying drawing, forming a part thereof.

The figure is a perspective view of a wardrobe showing my new design.

I claim:

The ornamental design for a wardrobe, as shown.

In testimony whereof I have hereunto set my hand in presence of two subscribing witnesses.

JULIUS BRAUSE.

Witnesses:

JOHN WAGNER,
PERRY H. PATTISON.
